DESIGN FOR A HANDBAG

Tina Leser, New York, N. Y.

Application July 9, 1941, Serial No. 101,984

Term of patent 3½ years

To all whom it may concern:

Be it known that I, Tina Leser, a citizen of the United States of America, residing in New York city, county of New York, and State of New York, have invented a new, original, and ornamental Design for a Handbag, of which the following is a specification, reference being had to the accompanying drawing, forming part thereof.

Fig. 1 is a side elevational view of a handbag showing my new design.

Fig. 3 is a rear view thereof.

I claim:

The ornamental design for a handbag, substantially as shown.

TINA LESER.
